OIL BURNER

William J. Fishel, Winston-Salem, N. C.

Application October 12, 1940, Serial No. 360,981

2 Claims. (Cl. 158—91)

This invention relates to oil burners and while it is designed primarily for use in connection with hot air circulators of the type to be set up in the rooms of residences, stores, and the like, it can also be employed within the furnaces of central heating systems.

An object of the invention is to provide a burner to which the fuel is supplied by gravity, there being contained within the burner a vaporizer in the form of a metal post of copper or other suitable metal highly efficient as a medium for absorbing and conducting heat.

A further object is to provide the burner with a new and novel arrangement of baffles combined with air intake ports by which thorough mixing of air with the generated fumes within the burner is effected to insure substantially complete combustion as well as elimination of smoke at the outlet of the burner.

Another object is to combine thermostat-controlled dampers with the burner, these being located where they can control the supply of fresh air to the burner at the most desirable points when needed to maintain substantially complete combustion at all times during the operation of the burner.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is an elevation of a heater equipped with the present improvements, a portion of the casing of the heater being broken away to show the burner therein.

Figure 2 is an enlarged central vertical section through the burner taken on the line 2—2, Figure 1.

Figure 3 is a section on line 3—3, Figure 2.

Figure 4 is a section on line 4—4, Figure 2.

Figure 5 is a section on line 5—5, Figure 2.

Referring to the figures by characters of reference, 1 designates the hollow body portion of the burner which, in the present instance, is frusto-conical, the body being tapered downwardly to a flat bottom 2 while the large upper end thereof opens into an outlet flue 3. The lower portion of the body is surrounded by a jacket 4 which can be cylindrical and the bottom 5 of which is formed with an annular series of air intake ports 6. A disk 7 is pivotally joined at its center to the bottom 5, as shown at 8 and constitutes a rotatable damper. This disk has an annular series of apertures 9 adapted to move

into and out of register with the respective ports 6. For the purpose of effecting movement of the damper, an ear 10 is extended upwardly therefrom and through a slot 11 in the bottom 5, this slot of course being at all times closed by the damper. To the ear 10 is secured the lower end 10 of a thermostat 12 the upper end of which is fixedly secured to the wall of the body 1 as indicated at 13. This thermostat can be formed of connected strips of metal having different coefficients of expansion so that temperature changes will cause the strip to bend in one direction or another thereby stepping up a corresponding movement of the damper so that the ports 6 can be partly or entirely opened or closed, thereby to control the flow of fresh air therethrough into the jacket 4.

Concentrically located on and secured to the bottom 2 of the body 1 is the enlarged base 14 20 of a post 15 which extends upwardly within the body to a point below but adjacent to the center of an opening 16 located at the center of a partition 17 which forms the top of a combustion chamber 18 in the lower portion of the body. Extending upwardly from the wall of the opening 16 is a flared outlet sleeve 19.

Superposed baffle rings 20, 21 and 22 are supported within the body 1 about the post 15. These rings are spaced from the post and if desired the middle ring 21 can be nearer the post than the lower ring 22 but more remote therefrom than the upper ring 20.

Formed in the body 1 below each of the baffle rings 20, 21 and 22 is an annular series of openings 23 which maintain communication between the combustion chamber 18 and the interior of the jacket 4. Another similar annular series of apertures 24 is located in the body 1 below the top or partition 17 and are for the same purpose.

An air intake flue 25 extends through the wall of body 1 and is provided, at its inner end, with a downwardly extending portion 26 coaxial with sleeve 19 and opening 16 but spaced from the sleeve as shown. The outer or inlet end of the flue 25 can be enlarged as shown at 27 and is adapted to be closed by a suspended damper 28 mounted to swing about a transverse pivot 29 at the upper end of the flue inlet. An arm 30 is extended from the upper end of the baffle and is so positioned that it will act as a weight normally to hold the lower end of the damper pressed outwardly against a stop flange 31 at the inlet end of the flue. A finger 32 is extended laterally from the damper at a point above its pivot 29 and is adapted to be engaged by the movable end of a thermostat 33 one end of which is secured to the jacket 4. This thermostat can be of the usual bi-metal type so that changes of temperature will cause it to press against or to move away from the finger 32, thereby causing the damper 28 either to open or close. The clos-

ing of the damper will of course be effected by gravity when pressure is removed from the finger 32.

An air-control flame spreader in the form of a disk 34 is suspended between sleeve 19 and the outlet end portion 26 of damper 25 by a rod 35 adjustably connected, as at 36, to a bi-metal thermostat 37 in the form of a strip which bridges the flue 3 and is supported at its ends on suitable brackets 38 or the like. Obviously variations in temperature adjacent to thermostat 37 will cause the rod 35 to move upwardly or downwardly, carrying with it the spreader 34 which thus acts to control the flow of air downwardly from flue 25. The disk or spreader 34 acts to divert the inflowing air radially so that it will mix at the margin of the disk 34 with the products of combustion issuing in a circular stream from the opening 16 and about the disk 34.

A pipe 39 is provided for supplying liquid fuel by gravity to the bottom portion of the body 1, it being understood that the flow can be controlled by a suitably located valve indicated generally at 40. This valve, when open, can be so constructed that the amount of fuel admitted to the burner will be just sufficient to maintain a thin film of liquid fuel on the bottom 2 while the fuel is burning. Means for opening and closing the valve has been indicated generally at 41 and can be controlled by a thermostat 42 so that when a room temperature reaches a predetermined degree, the valve can be either opened or closed.

When the valve 40 is open to admit liquid fuel to the body of the burner, fuel will accumulate in a thin film on the bottom 2 and about the base 14 of the post 15. It is then ignited and the products of combustion rising within the combustion chamber 18 will follow a circuitous path while mixing with jets of fresh air admitted through the openings 23 and 24. The amount of this air will be dependent on the position of the damper 7. This supply of air is sufficient for starting purposes. As the air surrounding the burner becomes heated, it will act on thermostat 33 to gradually open the damper 28, thus admitting fresh air to the flue 25 which will descend and be spread radially in all directions by the disk 34, thereby mixing thoroughly with the products of combustion issuing from the upper end of the sleeve 19. Consequently combustion will be further promoted and the heat in the burner intensified. As the air surrounding the burner is increased in temperature the damper 28 will open to a greater extent, thereby increasing the supply of air and as the heat resulting from combustion within the burner increases and the thermostat 37 shifts as a result thereof, the disk or spreader 34 will be moved gradually toward the outlet or lower end portion 26 of flue 25 with the result that while the size of the air stream will be cut down at this point, the velocity of the air will be increased, thereby increasing the spread of the flame over a greater area in the burner and correspondingly reducing its temperature as a result of the excessive fanning action of the air. As a result of this cooperation of the two members 28 and 34 a substantially predetermined temperature can be maintained in the burner based upon the temperature of the air in the conduit or space between the burner and the surrounding casing. Vaporization of the fuel is facilitated by the use of the base 14 and post 15 formed of copper or other metal which

has good heat-conducting properties, this post and base constituting a vaporizing core which will quickly convert unvaporized fuel into vapor when brought into contact therewith after the burner has been well started.

When the burner is cold, as during the starting operation, the openings in the bottom of jacket 4 are opened. Thus air is supplied freely to the fuel within the burner. As the temperature increases, however, the supply of air through the bottom 5 will be gradually cut off so that combustion thereafter will be dependent upon air supplied at damper 34 where it mixes with the vaporized fuel as before explained.

As before stated the burner can be set up within a room heater as shown, for example, in Fig. 1 wherein the casing of the heater has been indicated at 43. When thus located its lower portion is extended through and supported by an imperforate partition 44 so that air can flow upwardly therethrough solely through the burner. For central heating systems the burner can of course be set up within a furnace.

Should it be found desirable, a thermostat fuel-control valve could be arranged so as to cooperate with the damper-operating means so that the operation of the dampers and the fuel valve would be dependent one upon the other.

What is claimed is:

1. A burner for use in heaters comprising a body having a combustion chamber in the lower portion thereof provided with a flared outlet at its top, a jacket surrounding the combustion chamber and communicating therewith, said jacket having an air inlet, means for supplying liquid fuel to the bottom portion of the combustion chamber, an air flue opening into the body and downwardly toward the flared outlet of the combustion chamber, said flue having an air inlet at its outer end, means outside of but controlled by heat generated within the combustion chamber for increasing the flow of air into said inlet as the temperature in the burner rises, a spreader interposed between the flue outlet and the outlet of the combustion chamber, and a thermostat controlled by the heat in the burner for shifting the spreader toward the flue outlet as the temperature rises, thereby to increase the velocity and spread of the increased volume of air admitted through the flue inlet.

2. A burner for use in heaters comprising a body having a combustion chamber in the lower portion thereof provided with an outlet in its top, said combustion chamber having air inlet openings, a jacket surrounding the apertured portion of the combustion chamber and having an air inlet, means for supplying liquid fuel to the bottom portion of the combustion chamber, an air flue opening into the body and downwardly toward the outlet of the combustion chamber, said flue having an air inlet at its outer end, a spreading disk of greater diameter than the flue outlet and interposed between said outlet and the outlet of the combustion chamber, a thermostat within the burner and connected to the disk, a damper at the inlet of a flue, and a thermostat outside of but close to the burner and connected to the damper, said thermostats constituting means for simultaneously opening the damper and moving the disk toward the flue during a rise in temperature, thereby to increase the supply of air to the flue outlet and increase the velocity and spread of the air at said outlet.
